UNITED STATES PATENT OFFICE.

THOMAS DODDS, OF THESSALON, ONTARIO, CANADA.

INVALID-BED.

1,397,041.

Specification of Letters Patent. Patented Nov. 15, 1921.

Application filed February 19, 1921. Serial No. 446,280.

To all whom it may concern:

Be it known that I, THOMAS DODDS, a subject of the King of Great Britain, a resident of the town of Thessalon, Province of Ontario, Dominion of Canada, have invented certain new and useful Improvements in Invalid-Beds, of which the following is a specification.

This invention relates to improvements in invalid beds, and the objects of the invention are to provide a means whereby a portion of the spring mattress may be raised to bring patients to sit up position and simultaneously to provide means which will engage with the under portion of the knees and prevent the patient from slipping downwardly toward the bottom of the bed, to permit of the lower end or bottom and the upper or top end of bed being elevated so that the feet of the patient may be brought into position above that of his head or the head brought into a position above the feet with the body of the patient lying in an inclined position, to permit of the head piece and foot piece of the bed being folded down so as to clear the ends of the bed, in which position the bed may serve as an operating table and generally to adapt the bed to better perform the functions required of them. With the above and other objects in view, the invention consists essentially of the improved construction and arrangement of parts described in the following specification and accompanying drawings and set forth in the appended claims.

In the drawings:

Figure 1 is a perspective view of the bed embodying my invention.

Fig. 2 is a longitudinal section of the same.

Fig. 3 is a sectional detail of the foot of the bed.

Fig. 4 is a detail showing the drum and the ratchet and dog connection.

Referring to the drawings; A represents a bed comprising a frame 10 in which the frame 11 of a spring mattress is mounted. The frame 11 is provided along its lateral walls with lugs engaging a rod 12 to which is connected a plate 13 hingedly connected 50 to a second plate 14 having depending pro-

jections 15 extending inside of the mattress frame and carrying a transverse rod 16.

The rod 16 is connected, through the link 17 provided with notches 18 adapted to engage the rod 16, to an arm 19 pivotally connected to the mattress frame 11 as at 19^a. The arm 19 is fastened to one end of an arcuate member 19^b fastened to a head portion 20 connected to the mattress frame by the pivot 19^a. The connecting point of the 60 arm 19 and the arcuate member 19^b is provided with a pulley 21 engaged by a wire 22 which has one end fastened to the side rail of the bed. The wire 22 winds around a drum 23 carried by a transversely extending shaft 24 journaled on depending apertured ears 25 from the bed frame. One end of the shaft 24 is square in cross section so that when the upper pivoted portion 20 of the spring mattress is desired to be raised 65 the square end of the shaft is engaged by a crank and the same is rotated thereby winding the wire 22 around the drum 23 and drawing the arcuate member 19^b toward the head of the bed thereby raising the head portion 70 20 and the head of the patient lying thereon. The arm 19 being drawn upon the pivotal movement of the head portion 20, toward the head of the bed, transmits the pull through the link 17 to the rod 16 with which 75 the link is in engagement thereby raising the apex of the plates 13 and 14 which engage the under portion of the knees of the patient to prevent him from slipping downwardly in the bed.

The arm, link and arcuate member together with the wire and drum attachment are provided on both sides of the spring mattress frame so that the head portion 20 may be raised evenly.

The posts 26 of the lower end of the bed are formed hollow and in the same, hollow posts 27 are slidably mounted. To the top of the hollow post 27 is fastened one end of a wire 28 which extends downwardly inside 95 the post 27, and through the lower end of the same, engages a pulley 29 carried by a pin supported by arms extending from a collar 30 formed integral with the outer post 26. The wire 28 extends from the pul- 100

- ley, upwardly to the drum 31 carried by a transversely extending rod 32 journaled in the apertured ears 33 formed integral with the bed frame. The hollow post 27 is provided with a longitudinal front slot 27^a designed to afford a free passage for the pulley 29 on the ascension of the same when the tubular post 26 slides upwardly over the post 27.
- 10 The transverse rod 32 has one of its ends square in cross section and extending past the ear 33. Keyed to the rod 32 adjacent to the drum 31 is a ratchet wheel 40 designed to coact with a spring controlled dog 41 carried by an extension from the ear 33. A wire and drum construction is provided also in the second post 26 of the lower end of the bed, but the pawl and ratchet is only mounted adjacent one of the drums 31.
- 20 To raise the lower end of the bed the square end of the transverse rod is engaged by a crank and on rotating the same the wires will be wound around the drums 31 and prevented from unwinding by the spring controlled dog 41 being pressed into every notch of the ratchet 40. The outer posts 26 will thus be caused to slide over the inner posts 27 and the lower end of the bed consequently raised to the desired height.
- 30 When it is desired to bring back the bed to normal position the pawl 41 is disengaged from the ratchet by hand pressure and the wire unwound from the drums by means of the crank.
- 35 The posts 36 of the head or upper portions of the bed are of exactly the same construction and provided with the same equipment as the posts 26 of the lower end described above.
- 40 The head of the bed is worked like the lower end thereof, the constructive parts of the one being duplicated from those of the latter. The square extremities of the transverse rods 32 and 24 are made of uniform size so that the same crank can be used in working the same.
- 45 The head shaft 32 also carries adjacent to the drum 31 a ratchet 40 with which a spring controlled dog 41 is designed to coact.
- 50 When the upper end or head of the bed is desired to be raised the square end of the shaft 32 is engaged by a crank and rotated whereby the wires 28 will be wound around the drums 31 and will raise the outside posts 55 36 of the head of the bed to the desired height. The upper end of the bed is rotated back to normal position by disengaging the pawl 41 from the ratchet 40 and reversing the crank.
- 60 The foot of the bed is formed in two sections, the top section 34 being hingedly connected as at 35 to the bottom section, and the hollow posts 27 slidably mounted within the hollow posts 26 extending a little higher

than the hinge 35 so as to engage the upper 65 portion thereof and hold the same rigidly in straight position in alinement with the bottom section of the posts.

The sections 34 can be lowered by rotating on the hinges 35 after the lower end of the 70 bed has been raised a little so as to clear the section 34 from the overlapping posts 27.

The head of the bed is also formed in two sections 37 and 38, the upper section 37 being hinged to the lower sections at 39. The upper section can be rotated or lowered in a position parallel to the lower section 38 by freeing it from the hollow inner posts 27.

The lower ends and the upper end or head of the bed can both be raised and the sections 26 and 37 lowered and the bed may be used as an operating table whenever the same is needed.

It will be obvious that this bed can be very efficiently used, enabling a person to place 85 the patient in whatever position desired, very easily by the manipulation of a crank engaging the squared ends of the several transverse rods.

As many changes could be made in the 90 above construction and many widely different embodiments of my invention within the scope of the claims constructed without departing from the spirit or scope thereof, it is intended that all matter contained in the 95 accompanying specification and drawings shall be interpreted as illustrative and not in a limiting sense.

What I claim as my invention is:

1. An invalid bed having tubular posts at 100 the head and foot thereof apertured at the lower extremity, hollow posts telescoping within the tubular posts, flexible members connected to the hollow posts extending through the said apertures and winding 105 means carried by the bed frame and engaging the flexible members.

2. An invalid bed having tubular posts at the head and foot thereof apertured at the lower extremity, hollow posts telescoping 110 within the tubular end posts provided with a longitudinal slot on one side thereof, a pulley carried by each tubular-post and extending within the longitudinal slot, flexible members carried by the upper end of the 115 hollow posts and engaging the pulleys, and winding means carried by the bed frame and engaging the flexible members.

3. An invalid bed having tubular posts at the head and foot made of two sections, one 120 section being hingedly connected to the other intermediate of their length, inner posts telescopically mounted within the tubular posts and extending a little higher than the lower sections of the posts in order to engage the top sections thereof.

4. An invalid bed having tubular posts at the head and foot thereof apertured at the

lower extremity and formed of two sections, one section being hingedly connected to the other, hollow posts telescoping within the tubular posts and extending higher than the bottom section so as to engage the upper section of the posts, flexible members connected to the hollow posts extending through the said apertures and winding

means carried by the bed frame and engaging the flexible members.

In witness whereof I have hereunto set my hand in the presence of two witnesses.

THOMAS DODDS.
